UNITED STATES PATENT OFFICE

153,417

DESIGN FOR A FISHING REEL

Earle D. Clickner, Kalamazoo, Mich., assignor to
Shakespeare Company, Kalamazoo, Mich.

Application January 15, 1948, Serial No. 143,806

Term of patent 14 years

(Cl. D31—4)

To all whom it may concern:

Be it known that I, Earle D. Clickner, a citizen of the United States, residing in Kalamazoo, in the county of Kalamazoo and State of Michigan, have invented a new, original, and ornamental design for a Fishing Reel, of which the following is a specification, reference being had to the accompanying drawing, forming part thereof.

Fig. 1 is a top plan of a fishing reel embodying my new design.

Fig. 2 is an end elevational view of the same viewed from the left of Fig. 1.

Fig. 3 is an end elevational view viewed from the right of Fig. 1.

The dominant features of my design reside in the portions shown in full lines.

I claim:

The ornamental design for a fishing reel, as shown and described.

EARLE D. CLICKNER.
